HAIR BLOCKING PATTERN

Jack C. Fred, Atlanta, Ga.

Application September 8, 1949, Serial No. 114,513

1 Claim. (Cl. 132—45)

1

This invention relates to a hair curling pattern.

An object of this invention is to provide a pattern for use in the curling of hair, generally, and especially for use in home permanents, so that the curls may be evenly spaced and arranged in a definite pattern.

Another object of this invention is to provide a pattern which may be formed out of fabric, paper, plastic or the like, and which may be laid over the head. The pattern is formed with spaced slits through which groups of hair are adapted to be drawn and then formed into curls on the outer side of the pattern. After the curls are formed over the pattern, the latter is left on the head until the curls have set, and when the curls are being combed out the pattern is removed. Where the pattern is made out of paper it may be used only once, but where the pattern is made out of fabric or other material which will not readily tear, it may be used indefinitely.

The pattern herein disclosed is formed of several pieces which are designed for progressive mounting on the head so that the pattern will not interfere with the formation of the groups of hair.

With the above and other objects in view, my invention consists in the arrangement, combination and details of construction disclosed in the drawings and specification, and then more particularly pointed out in the appended claim.

In the drawing.

Figure 1 is a detail front elevation of a hair blocking pattern constructed according to an embodiment of this invention,

Figure 2 is a detail side elevation of the device,

Figure 3 is a rear elevation of the device,

Figure 4 is a plan view of the elements forming the pattern.

Referring to the drawing, the numeral 10 designates generally a T-shaped flexible pattern member which is adapted to be positioned on the head of a user. The T-shaped member 10 is formed of a head 11 and an elongated stem 12. The head 11 is provided with a plurality of transversely extending slits 13, and the stem 12 is formed with a plurality of spaced slits 14.

The slits 14 are disposed at right angles to the slits 13. The head member 11 is adapted to be positioned over the forward portion of the head of the user, with the stem portion 12 projecting rearwardly and downwardly over the back of the head.

A pair of elongated flexible strips 15 are adapted to be disposed one on each side of the

stem 12, and each strip 15 is provided with a plurality of transversely extending slits 16.

The head member 11 has disposed adjacent the central slit 13a thereof, the designation "center curl" as indicated at 17, and the slits extending from the opposite sides of slit 13a have numerals 18 disposed there-adjacent, with arrows 19 pointing outwardly from the center slit 17. The word "crown" is disposed at the forward end of the stem 12 as indicated at 19, and slits 14 have numerals 20 disposed there-adjacent, with numerals 20 reading outwardly, and arrows 21 are disposed between each pair of slits and are pointed rearwardly.

Each extension strip 15 has the word "begin" disposed at the forward end thereof, as indicated at 22, and the indication "1-R" as indicated at 23, is positioned adjacent the forward end of strip 15. The slits 16 are designated by numerals, reading in order from the inner end of strip 15, and arrows are pointed outwardly and disposed between the slits 16. There may be as many strips 15 as may be necessary to cover the head on each side of stem 12.

In the use and operation of this device, the T-shaped member 10 is placed on the head of the user, with the head or flange 11 extending crosswise adjacent the forehead. The hair is pulled through the slits 13 in groups, starting from center slit 13a and working outwardly through slits 13. The groups of hair which are pulled through slits 13a and 13 are then formed into curls in the normal manner, with the curls overlying the head or flange member 11. The curls on top of the head and extending toward the back are then formed through stem 12, beginning with the innermost one of the slits 14. By having the slits defined by numerals the user of this pattern will be able to quickly determine the number of curls which are to be or should be formed. After pattern member 10 has been applied to the head, with the curls formed on the outer side thereof, extension strips 15 may be applied to the head, one at a time, with the groups of hair being extended through slits 16. By providing a pattern as hereinbefore described, the pattern is progressively placed on the head and will not interfere with the formation of the groups of hair and the curls which are formed in such groups. After the curls have set, the pattern may be pulled over the curls and in the event the pattern is formed out of fabric, the pattern may be used indefinitely.

It will be understood that this pattern may be

formed out of any suitable flexible material, such as fabric, paper, plastic or the like.

I do not mean to confine myself to the exact details of construction herein disclosed, but claim all variations falling within the purview of the appended claim.

What I claim is:

A pattern for use in curling hair comprising a substantially T-shaped flexible member formed with spaced slits along the head thereof and with 10 spaced slits extending transversely along the stem thereof, the head of said member being adapted to be positioned across the front of the head of

the user and the stem of said member extending rearwardly over the top of the head of the user and terminating at the back thereof, and a pair of elongated transversely slotted strips positionable along side of said stem, the slits of said T-shaped member and of said pair of strips having groups of hair extended therethrough for forming into curls on the outer sides of said T-shaped member and said strips.
